CLAIM

The ornamental design for binoculars, as shown and described.

DESCRIPTION

FIG. 1 is a perspective view of binoculars showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is an enlarged perspective view thereof taken from FIG. 1.

The broken lines shown in FIG. 6 depict environmental subject matter only and the broken lines shown in FIGS. 1 and 8 demarcate the enlarged view of FIG. 8; all broken lines form no part of the claimed design.

1 Claim, 8 Drawing Sheets

FIG.1
